UNITED STATES PATENT OFFICE.

WILLIAM G. STUART, OF NUNHEAD, COUNTY OF SURREY, ASSIGNOR OF ONE-HALF TO ALBERT HENRY BELLINGHAM, OF PECKHAM, ENGLAND.

CAR-COUPING.

SPECIFICATION forming part of Letters Patent No. 400,508, dated April 2, 1889.

Application filed November 6, 1888. Serial No. 290,149. (No model.) Patented in England March 14, 1887, No. 3,830; in France May 6, 1887, No. 183,374, and in Germany May 6, 1887, No. 42,380.

To all whom it may concern:

Be it known that I, WILLIAM GEORGE STUART, a subject of Her Majesty the Queen of Great Britain, residing at Nunhead, in the 5 county of Surrey, England, have invented a new and useful Improvement in Railway-Car Couplings, (for which I have obtained a patent in Great Britain, No. 3,830, bearing date March 14, 1887; in France, No. 183,374, 10 and in Germany, No. 42,380, both bearing date May 6, 1887,) of which the following is a specification.

My invention relates to couplings for railway wagons or cars, the invention being particularly adapted for "goods" or freight cars, 15 the object being to provide a simple and cheap device for coupling up the adjacent ends of two cars, which can be conveniently and safely operated by a person from outside 20 of the buffers.

To clearly explain the nature of my invention, reference is made to the accompanying drawings, in which—

Figure 1 represents, partly in section, the 25 abutting ends of two cars with the coupling so raised that the link end of one is about to drop into the hook of the other. Fig. 2 represents, partly in section, the completion of the coupling operation where the link of one 30 car is engaged with the hook of the other, the rods which the person or official has used to effect this having dropped into their normal position. Fig. 3 represents, partly in section, the car ends parted and as it would be in the 35 act of traveling. Fig. 4 is a plan of Fig. 3, but showing only the main beams of the car, the position of the body being indicated by dotted lines; and Fig. 5 is a front elevation of one of the links detached.

To the ordinary draw-bar hook, A, I attach 40 a link, B, the construction of which is shown perhaps more clearly in Fig. 5. At right angles to the link-opening projects a hook, C, the form which I consider best for this being 45 that shown in the drawings. At a convenient point beneath the frame-work of the car I place the device for lifting these coupling-hooks. This consists of a metal rod or bar, D, the outer ends of which are turned down

at the sides of the car to form handles E, as 50 shown, while the center portion is bent into the form of a crank, as shown at F, such portion serving when raised to lift the hook B, as shown in Figs. 1 and 4. The handles E are entirely out of the way, as they are protected as well as prevented from striking persons alongside of the line by the body of the car, which overlaps the frame-work timbers, 55 as shown by dotted lines in Fig. 4. This rod D is preferably supported by metal bearing- 60 plates a a, which are secured to the frame-work of the car, while to further support it at the center, as well as to prevent any side- 65 wise movement, clips b b, secured to the frame-work, are placed close up to the crank por- 70 tion F.

The operation of the device will be readily understood; but it may briefly be described as follows: The person or official wishing to couple up the cars will stand outside of the 75 buffers, and by means of the two handles E E, which, for convenience, are brought slightly forward, as shown, will raise the cranked portions F of the rods D, thus lifting both links B, say, into the position shown in Fig. 1, al- 80 lowing the link end e of one to drop into the hook C of the other, as shown in Fig. 2, when the handle E may be dropped, as the cou- 85 pling is thus effected. It will of course be evident that it is immaterial which link is raised first or above the other, as either link end e will engage with either hook C. As the cars start off, the links are drawn into the 90 position shown in Fig. 3. To uncouple, the car ends must be close up, as usual. The lower 95 link is raised slightly by means of the handle E, and the link end e of the other is lifted, by means of the other handle E, from engagement with the hook C of same.

For the purpose of coupling up a car which 90 may not be fitted with this apparatus and which has the usual links depending from the hook A, I retain this hook A, as shown, for the purpose of receiving one of the ordinary links; but it will be evident that such is not 95 essential to my invention, as the link B may be hung from any other suitable draw-bar head.

What I claim, and desire to secure by Letters Patent, is—

In a car-coupling, the link B, depending from a hooked draw-bar head, A, having a link end, e, and hook C, in combination with a cranked rod, D, for raising same, having handles E, and being suitably attached to the car, substantially as described.

In testimony whereof I have hereunto set my hand in the presence of two subscribing witnesses.

WILLIAM G. STUART.
